UNITED STATES PATENT OFFICE.

CLAYTON ALLEN TURNER, OF MILWAUKEE, WISCONSIN.

GARMENT-SUPPORTER.

SPECIFICATION forming part of Letters Patent No. 440,449, dated November 11, 1890.

Application filed May 28, 1890. Serial No. 363,472. (No model.)

To all whom it may concern:

Be it known that I, CLAYTON ALLEN TURNER, of Milwaukee, in the county of Milwaukee and State of Wisconsin, have invented a new and useful Improvement in a Stocking-Supporter, of which the following is a description, reference being had to the accompanying drawings, which are a part of this specification.

10 My invention relates to the novel features in a stocking-supporter hereinafter to be particularly claimed.

In the drawings, Figure 1 represents my complete device as arranged and used in connection with a short-legged stocking or sock such as is worn by gentlemen. Fig. 2 is an edge view of the clip or safety-buckle adapted for securing the device to the stocking. Fig. 3 is an end view of the safety-buckle. Fig. 4 20 is a view of the safety-buckle with a modified form of device for connecting it with the elastic band.

In the drawings, the dotted lines A represent the outline of a leg and the dotted line 25 B the top of the stocking. A metal plate C has its lateral edges curved outwardly around and upon the extremities of a wire D. These curved sides or wings E E of the plate are closed tightly down on the ends of the wire D 30 and secure it rigidly to the plate C. At the lower end of the plate C a central projection F therefrom is curved rearwardly upon itself, forming a lateral aperture through which the tongue G of the buckle is inserted and in 35 which it is hinged. The tongue G is formed of a piece of wire sharpened at its extremities, its central part being inserted and located in the projection F, which forms a hinge or eye for its reception, the two ends of the

40 wire of which the tongue is formed being bent at right angles at a little distance from the projection or hinge F. A part H, projecting from the upper end of the plate C centrally, is curved outwardly and downwardly 45 and terminates in a cross-head projecting laterally beyond the sides of the shank of the projecting part H, which extended parts are turned inwardly toward the plate C at both ends, forming a keeper I, adapted to receive 50 thereunder and retain the otherwise free ends of the tongue G. The parts or shanks K K of

the tongue G near to the projecting part or hinge F are arranged to bear against the lower edge of the plate C when the free ends of the tongue are carried inwardly toward the keeper 55 I and hold them when within the keeper firmly against the inner sides of the keeper, being only capable of being released therefrom by sufficient force to spring the ends of the tongue inwardly away from the keeper, the 60 tongue being constructed of elastic wire therefor. The two parts of the wire D, the ends of which are secured rigidly in the plate C, are brought together at a little distance from the end of the plate and are twisted upon each 65 other for a distance, forming a stem L, the medial part of such wire being formed at the upper end of the stem L into a ring M. An elastic band N is secured permanently at one end to the ring M, and at its other end is inserted adjustably in the buckle or clasp O of the hook P. The clasp O is provided with two laterally-extending slots, there being an intermediate bar about which the band N is passed from the under side, and whereby the 75 band is secured adjustably in the clasp of the hook. The hook is adapted to engage the ring M and retain the band N about the leg with the buckle depending therefrom. The tongue G of the buckle is adapted to be inserted 80 through the stocking and secured by forcing its free ends beneath the keeper I.

In the modified form of device shown in Fig. 4 a chain L' is used instead of the stem L to connect the buckle with a ring M', used 85 instead of the ring M on the stem L.

A flexible cord may be used instead of the chain L'; but I prefer the rigid stem L either to a chain or cord.

What I claim as new, and desire to secure 90 by Letters Patent, is—

1. A stocking-supporter consisting of an elastic band N, provided at one end with an adjustable hook P, and a ring M secured to the other end of the band N, in combination 95 with a buckle consisting of a metal plate C, provided with a swinging tongue G and a keeper I, and a stem L, rigid to the buckle, the ring M being constructed as a part of the stem L, substantially as described.

2. In a garment-supporter, a buckle constructed of a metal plate C, the central lower

part of which is turned rearwardly, forming a bearing and support for the tongue, the central upper part of which plate is turned forwardly and has a laterally-extending cross-head forming a keeper I, and the sides of which plate are turned about and upon the two extremities of a stem-wire D, securing the wire rigidly thereto, a tongue G, centrally pivoted on the plate C, the tongue being in two parts bent at right angles at a little distance from its central support in the plate C, and

the stem-wire D, having its extremities secured rigidly in the plate C and projecting therefrom at the upper end of the plate, substantially as described.

15

In testimony whereof I affix my signature in presence of two witnesses.

CLAYTON ALLEN TURNER.
